PROPELLER

Roger E. Lorenzen, Niles, Mich.

Application September 30, 1937, Serial No. 166,555

3 Claims. (Cl. 170—159)

This invention relates in general to a propeller for use with airplanes, boats, fans and the like, and has more particular reference to a propeller with adjustable blades adapted to be easily set 5 at any desired angle with respect to the hub for varying the pitch thereof.

An important object of the invention is in the provision of a propeller made of plastic material and cast in one piece.

10 A further object of the invention is in the provision of blades which vary their contour from the inner to the outer end so that they can be easily adjusted and set at various different pitches with respect to the hub or holder.

15 A still further object of the invention is in the provision of an adjustable propeller having blades adapted to be yieldingly set in any desired position in the hub prior to the attachment of the hub to its rotating shaft.

20 A still further object of the invention is in the provision of a clamping hub or holder, and for a plurality of blades in which the blades are separately adjustable to vary their pitch and each blade is resiliently retained in any position in 25 which it is set prior to the application of the propeller to a rotating shaft.

Other and further objects will appear herein-after, the preferred embodiment of the invention being illustrated in the accompanying drawing, in 30 which:

Fig. 1 is a perspective view of a two-bladed propeller attached to the end of a shaft;

Fig. 2 is a sectional view of the hub or blade holder;

35 Fig. 3 is a detail of the attached end of one of the blades;

Fig. 4 is a section taken on the line 4—4 of Figure 3;

Fig. 5 is a perspective illustrating the method 40 of setting the blades at different pitches;

Fig. 6 is an enlarged view of one of the blades and the holder showing the pitch mark on the blade; and

Fig. 7 is a plan view of a three-blade holder.

45 This invention relates particularly to a propeller with adjustable blades at the same or different pitches prior to the attachment of the propeller to its rotating means. The structure herein shown is particularly adapted for the use of small or model airplanes in which it is desired to vary the pitch of the propeller blades under different conditions, and for motors of different sizes. However, adjustable propellers of this type 50 may also be used wherever propellers are used,

for boats, out-board motors, fans and also for larger aircraft.

It is contemplated that the separate blades will be made of plastic material such as Bakelite, or other condensate products, which are both light 5 and strong, and for propellers of fixed pitch the blades and central mounting may be cast or formed integrally of the same material requiring no separate hub. The blades may also be made of wood or light-weight material for adjustment, 10 as herein set forth.

Referring now more particularly to the drawing, a two-bladed propeller is shown in Figure 1, having separate blades 10 mounted at the ends of a hub or holder comprising two similar parts 15 11 which when placed together form opposite semi-circular hubs with transverse attachment bores 12 through which a fastening member 13 may be inserted for rigidly attaching the propeller to a shaft 14, or other rotating part. 20

Each of the blades is formed near its inner end with a straight portion 15 of the uniform size at the extremity of which is a flange 16 preferably rounded at the outer edges. At the inside of the hub members is a straight portion 17 at 25 the inner end of which is a curved groove or depression 18 adapted to receive the portions 15 and 16 respectively of the blade. Longitudinal steel wires 19, or other suitable reinforcing structures, such as 19^a, as indicated in Fig. 1, may be 30 molded or cast in the blades.

At the outer extremities of the hub sections are grooves 20 for setting spring rings 21 therein. In assembling a propeller, the spring rings are commonly placed on the attachment ends of the 35 blades, the blades will ride in the hub parts 11 and the spring rings 21 are slipped up over the ends and into the grooves 20, thereby yieldingly holding the hub halves together and the blades clamped loosely therein. 40

It is to be understood that the blades vary in shape or contour throughout the length of the blade. That is, the pitch of the blade is increased from the inner portion outwardly. By providing each blade with separate marks designated A, B, 45 C, D and the like, which relate to variations in curvature on the pitch of the blade, the blade itself may be set in its holder by applying to the flat or inner side of the blade an angular setting plate or setting device 22 referred to an adjacent plane surface, or as shown in Fig. 5, the assembled propeller may be referred to rectangular co-ordinates x—x, y—y, one of which is provided with special graduations a, b, c, d, etc., referred to the length of the blade from the common axis, 50 55

and in order to set a blade at any desired pitch, an angular setting device 22 is placed upon a plane surface in any desired setting position with one edge to engage the inner face of a blade and by adjusting the blade in its holder it will conform to the contact surface 23 of the setting device at that position. Thus the position of any blade may be adjusted in its holder corresponding to the pitch desired, and each of the blades 10 may be set correspondingly, or the blades may be given different pitches in the same holder. The holding spring rings 21 permit different adjustment of the blades in the holder, and when the propeller thus set is applied to a shaft for 15 rotating it, the fastening device 13 clamps the holder halves 11 tightly against the ends of the blades, holding them firmly in their set position. It is also contemplated that a multi-blade holder 25, as shown in Figure 7, consisting of similar 20 upper and lower clamping plates secured together by fastening screws 26 may be employed for propellers having more than two blades. The separate blades may be individually adjusted, and clamped in place by the holder.

25 In this manner a simple adjustable propeller may be produced, which is capable of easy adjustment and variation, the blades being separately variable for adjustment of pitch and being releasably held for firmly clamping them in 30 any position in which they are set prior to their attachment to the shaft or other means by which they are rotated.

I claim:

1. In an adjustable propeller having blades 35 rotatable in a hub about a longitudinal axis, and the pitch of the blade increasing as its distance from the hub of the propeller, the method of varying and setting the pitch of the blade which consists in providing the blade on one surface 40 with a series of graduations at various distances

from the hub of the propeller and adapted to be referred to a plane surface upon which the propeller is placed, such that an angular setting device may be inserted between the surfaces of the plate and the surface upon which the propeller is supported at one of the graduations, and the blade rotated about the longitudinal axis to conform the surface to the edge of the setting device depending upon its position with respect to the pitch marks of the blade on the setting 10 surface.

2. An adjustable propeller having blades mounted to turn about a longitudinal axis in a hub, the pitch of each blade varying as its distance from the hub, and having graduations on 15 the blade indicating distance from the hub; and an angular setting device having one surface to engage a reference surface adjacent the blade and another surface to engage the surface of the blade at various distances from the hub in accordance with the graduations for setting the pitch of the blades.

3. An adjustable propeller having separate blades, a hub having separable plates in which 25 the blades are rotatable about longitudinal axes, means for resiliently clamping the hub plates together so that the blades can be rotated upon said axes for setting them, the pitch of each blade varying as its distance from the hub, and having marked graduations along the blade so that an 30 angular setting device relative to the pitch of the blade may be inserted between the blade surface and a plane supporting surface at different locations along the blade relative to the graduations, the blade being rotated upon its axis to engage such device for setting each blade at the desired pitch, and means for firmly clamping the hub plates together to hold the blades as set.

ROGER E. LORENZEN. 40
